Primary Examiner—Carol Rademaker

(57) **CLAIM**

The ornamental appearance for a bottle, as shown and described.

DESCRIPTION

FIG. 1 is a top, front, and left side perspective view of a bottle in accordance with my new design;
FIG. 2 is a front elevation view thereof;
FIG. 3 is a right side elevation view thereof;
FIG. 4 is a left side elevation view thereof; and,
FIG. 5 is a bottom plan view thereof.
The broken lines shown in the drawings are for environmental purposes only and form no part of the claimed design.
